UNITED STATES PATENT OFFICE.

ALBERT E. LIPP, OF PHILADELPHIA, PENNSYLVANIA.

PHOTOGRAPH-PRINTING DEVICE.

1,073,430.

Specification of Letters Patent. Patented Sept. 16, 1913.

Application filed December 13, 1912. Serial No. 736,530.

To all whom it may concern:

Be it known that I, ALBERT E. LIPP, a citizen of the United States, residing at Philadelphia, in the county of Philadelphia and State of Pennsylvania, have invented 5 certain new and useful Improvements in Photograph-Printing Devices, of which the following is a specification.

My invention relates to photograph printing devices and has for its object to provide, 10 first, a novel means whereby photographic prints having white borders may be quickly and uniformly produced; secondly, a novel means whereby the border controlling devices may be quickly adjusted to prints and 15 negatives of different sizes; thirdly, a novel means of gaging the printing paper with respect to the border controlling devices and for holding the negatives in different positions with respect to the border controlling 20 devices so that parts or all of the negatives may be printed; fourthly, a novel means for controlling the contact board and for yieldingly holding it in the closed position; and, 25 fifthly, a novel means for holding a vignetting device in operative position all as will be hereinafter fully described and particularly claimed.

In the accompanying drawings, illustrating 30 my invention: Figure 1, is a front elevation of my improved photograph printing device. Fig. 2, is an elevation of the device with the contact board and its raising spring broken away. Fig. 3, is a vertical section, 35 on line 3—3 of Fig. 1. Fig. 4, is a horizontal section, on line 4—4 of Fig. 1. Fig. 5, is a rear elevation of the device. Figs. 6, and 7 are views similar to Fig. 2 showing modifications of the invention.

40 Referring to the drawings, 2 designates a frame which may be of any shape and size for its intended purpose. The frame 2 is provided with an exposure opening 5 therein, through which light may pass in printing photographs. In the present embodiment of my invention, the frame 2 is in the form of a hand frame, provided with a suitable handle 6 and adapted to be moved about by hand. It will be understood, however, that 45 the frame 2 may be a fixture and form a part of a wall of a dark room in which the

photographic prints are made. The forward face of the frame 2 is provided with a depression around the opening 5, and seated in the depression is a clear glass 7 covering 55 one side of the opening 5 and having its outer face flush with the forward face of the frame 2.

Arranged on the forward face of the frame 2 is an L-shaped member 8 and a contact board 9. The member 8 comprises an arm 10 arranged adjacent the top of the board 9 and an arm 11 arranged adjacent one side of the board 9, the top and one side of the board 9 being fitted to the arms 10 60 and 11, respectively, of the L-shaped member 8, as shown. The top of the contact board 9 is hinged to the arm 10 by means of suitable hinges 12, so that the board 9 may be moved on its hinges and from the forward face of the frame 2 and the forward face of the glass 7.

Located between the L-shaped member 8 and the forward face of the frame 2 is a second L-shaped member 13 which is secured 75 to the member 8 and forms, in effect, a part thereof. The L-shaped member 13 is made very thin, preferably of sheet metal, and it extends from the two arms 10 and 11 of the member 8 and forms an L-shaped flange located 80 between the forward face of the glass 7 and the inner or contact face of the board 9 along the top and one side thereof, for a purpose hereinafter explained.

The members 8 and 13 are bodily movable 85 toward and from the forward face of the frame 2 and they are supported by two flat springs 14. The upper ends of the springs 14 bear against a rib 15 on the top of the frame 2 and the lower ends of the springs 90 14 extend between the L-shaped members 8 and 13 and are secured to the member 8 by nails or screws. The springs 14 extend from the member 8 to the rib 15 in spaced relation to the forward face of the frame 2, 95 and the springs are held in the position shown with relation to the frame 2 by screws 16 which extend through openings in the springs and are screwed into the frame 2 and have heads engaging the outer faces 100 of the springs 14, causing them to press the members 8 and 13 toward the forward face

of the frame 2, or the forward face of the glass 7, or both. By adjusting the screws 16 in or out the pressure of the springs 14 may be nicely regulated.

5 The lower portion of the arm 11 of the member 8 is provided with a flat spring arm 17 which extends around the outer edge of the arm 11. One end of the spring arm 17 is secured to the arm 11 and the other end thereof is provided with an opening which receives a pin 18 projecting from the side of the frame 2. The spring arm 17 is formed with a bend 19 extending outwardly from the face of the arm 11, and the free end of the arm 17 is flared outwardly, at 20. When the bend 19 is pressed toward the arm 11, the flared end 20 slides over the end of the pin 18 and forces the free end of the arm 17 outwardly until the opening therein comes 15 into registry with the pin 18, when the arm 17 springs back toward the frame and the pin 18 enters the opening, thus causing the spring arm 17 to press the lower end of the arm 11 yieldingly toward the forward face 20 of the frame 2.

The negative 21 from which the prints are to be made is interposed between the member 13 and the forward face of the frame 2 and rests against the forward face 30 of the glass 7. In placing a negative in this position, the spring arm 17 is first disengaged from the pin 18 and the members 8 and 13 are sprung outwardly from the frame 2, and after the negative has been adjusted 35 to the desired position, the members 8 and 13 are released and the spring arm 17 is engaged with the pin 18, thus clamping the negative 21 in position. By the construction shown, it will be observed that the negative 21 may be adjusted to bring any portion 40 thereof, say for example, the head of a person on the negative, toward or from the inner edges of the two arms 10 and 11 of the L-shaped member 8. The inner edges of the 45 arms 10 and 11 form stops for the top and left hand side edges of the printing paper 22 when it is placed upon the negative 21. It will thus be seen that the printing paper 50 may be quickly and properly positioned with relation to the portion of the negative desired to be printed each time the contact board 9 is moved to the open position and the printing paper inserted, in printing a number of similar photographs.

55 To produce white borders around the edges of the photographic prints, I provide a thin L-shaped member 23, the two arms of which are clamped with the negative 21 between the forward face of the frame 2 and 60 the L-shaped member 13, the inner edges of the members 13 and 23 forming a rectangular opening through which light may pass to and through the negative 21 in making prints. The ends of the arms of the

member 23 lap the ends of the arms of the members 13 and the member 23 may be adjusted to different positions to vary the size of the opening formed between the members 13 and 23 to suit different requirements. When the member 23 is properly adjusted 70 for a sheet of printing paper of a given size, the paper is placed upon the negative and the inner edges of the two members 13 and 23 with the upper and left hand edges of the paper against the arms 10 and 11 of the 75 member 8, forming the paper gage. In this position, the edge portions of the paper extend over the edges of the members 13 and 23 uniformly around the paper, and the edges of members 13 and 23 prevent the light from 80 reaching the edges of the paper, when the paper is pressed against the negative by the contact board 9, in printing, thereby producing the white bordered prints.

Secured to the lower portion of the contact board 9 is one end of a flat spring arm 24 which extends from the board 9 around the bottom of the frame 2, forming a hook adapted to engage a face 25 of the frame 2 and to press the lower portion of the contact board 9 toward the frame 2, while the springs 14 press the upper portion of the board 9 toward the frame, when a sheet of printing paper is clamped between the negative 21 and the contact board 9. The spring 95 arm 24 is provided with an outwardly flaring or beveled end 26, so that when the contact board is moved to the closed position, hand pressure against the arm 24 will cause the flaring portion 26 to engage the bottom 100 edge of the frame 2 and force the free end of the arm downwardly until its hooked free end is in position to spring upwardly and engage the face 25 and hold the contact board in the closed or clamping position. 105 When it is desired to move the board from the closed to the open position, it is merely necessary to move the arm 24 to free its hooked end from the face of the frame 2.

To automatically move the contact board 110 9 to the open position shown by dotted lines in Fig. 3, when the spring arm 24 is moved to free its hooked end from the face 25, I provide a flat spring 27 which embraces the top of the frame 2 and is secured thereto by 115 a screw 28. The spring 27 extends from the screw 28 forwardly and downwardly adjacent the forward face of the contact board 9; and the lower end portion of the spring 27 is inserted into the space between a bar or 120 bracket 29 and the forward face of the contact board 9, the bar or bracket 29 being secured to the contact board. The spring 27 exerts forward and upward pressure against the bracket 29, and when the hooked end of 125 the arm 24 is freed from the face 25, the spring 27 raises the contact board to the open or dotted line position shown in Fig.

3. As the spring 27 is raising the board 9 to the dotted line position, and when it reaches the dot-and-dash line position, shown in Fig. 3, the end portion of the 5 spring 27 extending beyond the bracket 29 engages the forward face of the board 9 and exerts a downward pressure thereon, at 30, while the main body of the spring continues to exert an upward pressure on the bracket 10 29, at 31, as the spring continues to raise the board 9 until it comes to a stop at the dotted line position, its final movement being cushioned by the engagement of the 15 spring 27 with the face of the contact board 9, as the end portion of the spring slides through the bracket 29 and over the face of the board 9.

Formed in the frame 2 and extending around three sides of the opening 5, near the 20 rearward face of the frame, is an undercut groove 32, forming guides to receive a vignetting glass 33 and a substantially opaque vignetting board 34, the glass 33 and board 34 being arranged face to face 25 and inserted into the groove 32 from the open top thereof. The glass 33 and board 34 cover the rearward portion of the opening 5 and they are retained in place by the rearward end portion 35 of the spring 27, the 30 end portion 35 being formed into a latch adapted to be depressed when the glass 33 and board 34 are inserted or removed, and to engage the edges thereof and hold them in place. The glass 33 and board 34 are 35 supported in the groove 32 in spaced relation to the negative 21, when it is desired to print vignetted photographs. The glass 33 is provided with a thin coating of porcelain 36 to diffuse the light in passing there- 40 through, and the board 34 is provided with a suitably located opening 37, smaller than the opening 5 through which the light passes in printing the vignetted photographs in the usual manner.

45 In the modification shown in Fig. 6, the L-shaped member 13 is omitted and two projections or fingers 38 are provided to engage and hold a negative 39 inwardly of the two arms 10 and 11 of the L-shaped member 8 50 when it is desired to produce a white border at the extreme edge or beyond the edge of the negative. The fingers 38 are carried by the L-shaped member 8, and the inner face of the member 8 is adapted to engage the 55 negative when it is inserted between the member 8 and the forward face of the frame 2. In this construction, I employ a mask 40 60 extending entirely around the negative, to shut out the light to produce white bordered photographs, and the mask 40 may be pasted to the clear glass 7, or it may be clamped in place by the fingers 38 on the member 8.

In the modification shown in Fig. 7, the

L-shaped member 8 may only perform the 65 functions of a holding device for the negative 41 and a gage for the printing paper 42 when it is not desired to print white bordered photographs.

I claim:

1. In a photograph printing device, the combination of a frame having an opening therein, an L-shaped negative support on said frame adjacent two walls of said opening and having a negative-engaging face 75 movable toward and from said frame, yielding means connected to one arm of said L-shaped support and pressing said face toward said frame, a contact board movable toward and from said opening and having 80 one end hinged to the arm of said L-shaped support to which said yielding means is connected, and means for clamping the end of said board opposite to the hinged end thereof to said frame. 85

2. In a photograph printing device, the combination of a frame having an opening therein, a negative support on said frame adjacent said opening and having a negative-engaging face movable toward and from 90 said frame, a spring having one part secured to said frame and another part secured to said support and pressing said face toward said frame and guiding said support when moved toward or from said frame, a 95 contact board hinged to said support and movable toward and from said opening, and means for clamping said board to said frame.

3. In a photograph printing device, the combination of a frame having an opening 100 therein, an L-shaped negative support on said frame adjacent two walls of said opening and having a negative-engaging face 105 movable toward and from said frame, yielding means connected to one arm of said L-shaped support and pressing said face toward said frame, means for clamping the other arm of said L-shaped support to said frame, a contact board movable toward and from said opening, and means for clamping 110 said board to said frame.

4. In a photograph printing device, the combination of a frame having an opening therein, an L-shaped negative support on said frame adjacent two walls of said opening and having a negative-engaging face 115 movable toward and from said frame, yielding means connected to one arm of said L-shaped support and pressing said face toward said frame, means for yieldingly 120 clamping the other arm of said L-shaped support to said frame, a contact board movable toward and from said opening, and means for clamping said board to said frame. 125

5. In a photograph printing device, the combination of a frame having an opening therein, means for supporting a negative ad-

adjacent said opening, a contact board movable toward and from said opening, and a spring arm clamping said board to said frame, said arm having one end secured to said board and the other end hooked around a part of said frame.

6. In a photograph printing device, the combination of a frame having an opening therein, means for supporting a negative adjacent said opening, a contact board movable toward and from said opening, a spring arm clamping said board to said frame, said arm having one end secured to said board and the other end hooked around a part of said frame, and the hooked end of said arm having a beveled portion arranged to engage said frame and force the hooked end of the arm outwardly as it is moved into clamping position.

7. In a photograph printing device the combination of a frame having an opening therein and provided with a part having a negative supporting face adjacent said opening, a contact board movable toward and from said opening to closed and open positions, and a negative supporting member extending between said face and said board when the latter is in closed position, said face and said member being adapted to hold a negative therebetween.

8. In a photograph printing device, the combination of a frame having an opening therein and provided with a part having a negative supporting face adjacent said opening, a contact board movable toward and from said opening to closed and open positions, a part adjacent said board when said board is in the closed position, yielding means pressing said part toward said frame, and a negative supporting member carried by said part and extending between said face and said board when the latter is in the closed position, said face and said member being adapted to hold a negative therebetween.

9. In a photograph printing device, the combination of a frame having an opening therein and provided with a part adapted to support a negative adjacent said opening, a contact board movable toward and from said opening to closed and open positions, a part adjacent said board when said board is in the closed position, yielding means pressing said part toward said frame, and an L-shaped member covering a part of the contact face of said board when said board is in the closed position, said member being held in place by the second named part.

10. In a photograph printing device, the combination of a frame having an opening therein and provided with a part adapted to support a negative adjacent said opening, a contact board movable toward and from said opening to closed and open positions, a pair of members each having two arms

lapping the two arms of the other, said members forming an opening therebetween and covering a part of the contact face of said board when said board is in the closed position, one of said members being adjustable relative to the other to vary the size of the opening therebetween, and means holding said members in position and permitting movement of said board toward and from said members.

11. In a photograph printing device, the combination of a frame having an opening therein and provided with a part adapted to support a negative adjacent said opening, a contact board movable toward and from said opening to closed and open positions, a pair of members each having two arms lapping the two arms of the other, said members forming an opening therebetween and covering a part of the contact face of said board when said board is in the closed position, one of said members being adjustable relative to the other to vary the size of the opening therebetween, and yielding means holding said members in position and permitting movement of said board toward and from said members, said yielding means being connected to one of said members and causing it to press against the other of said members.

12. In a photograph printing device, the combination of a frame having an opening therein, means for supporting a negative adjacent said opening, a contact board movable toward and from said opening to closed and open positions, a part connected to said board, and a spring connected to said frame and engaging said part and operative to move said board from the closed to the open position when said board is released, said spring exerting pressure against said part in one direction and against said board in a reverse direction and retarding the final movement of said board as it reaches the open position.

13. In a photograph printing device, the combination of a frame having an opening therein, means for supporting a negative adjacent said opening, a hinged contact board movable on its hinge toward and from said opening to closed and open positions, a bracket secured to said board, a spring secured to said frame and extending between said bracket and said board and operative to move said board from the closed to the open position when said board is released, said spring exerting pressure against said bracket in one direction and against said board in a reverse direction and retarding the final movement of said board as it reaches the open position.

14. In a photograph printing device, the combination of a frame having an opening therein, a contact board movable toward

and from said opening to closed and open positions, means for supporting a negative on one side of said frame adjacent said opening, a vignetting device supported on the other side of said frame adjacent said opening, a spring embracing a part of said frame and secured thereto, one end of said spring tending to move said board to the open position, and the other end of said

spring forming a yielding retaining arm 10 holding said vignetting device in place.

In testimony whereof I affix my signature in presence of two witnesses.

ALBERT E. LIPP.
